UNITED STATES PATENT OFFICE.

ALLEN E. OSTRANDER, OF PATERSON, NEW JERSEY, ASSIGNOR TO
AMERICAN CAR & FOUNDRY COMPANY, OF ST. LOUIS, MISSOURI,
A CORPORATION OF NEW JERSEY.

BODY-BOLSTER.

No. 836,134.

Specification of Letters Patent.

Patented Nov. 20, 1906.

Application filed March 29, 1906. Serial No. 308,745.

To all whom it may concern:

Be it known that I, ALLEN E. OSTRANDER, a citizen of the United States, residing at Paterson, New Jersey, have invented a certain new and useful Improvement in Body-Bolsters, of which the following is a full, clear, and exact description, such as will enable others skilled in the art to which it appertains to make and use the same, reference being had to the accompanying drawings, forming part of this specification, in which—

Figure 1 is a plan view of a body-bolster embodying the features of my invention. Fig. 2 is a side elevation thereof. Fig. 3 is a detail view taken on the line 3 3 of Fig. 2, and Fig. 4 is a detail view showing the slot with which the center sills are provided to permit the passage therethrough of the continuous tension-plate.

20 This invention relates to body-bolsters for railway-cars; and the object of my invention is to provide a bolster possessing great strength and which can be manufactured cheaply.

25 The bolster which I have herein illustrated as embodying the preferred form of my invention consists of a casting which is recessed at its center to receive the center sills of the car, said casting being reinforced and strengthened in a novel manner.

Referring to the drawings, which represent the preferred form of my invention, 1 designates the bolster, consisting of a casting that is approximately I-shape in cross-section and which is provided at its center with a wide recess to receive the center sills 2, herein shown as I-beams. The bottom flanges of the I-beam center sills rest on the flange 3, forming the bottom of the recess in the bolster, and fillers 4 or diaphragms provided with continuous flanges are interposed between the center sills, said fillers being arranged with their flanges projecting in opposite directions. The flanges 5 at the ends of the fillers are connected to the webs of the center sills by rivets 6, and the bottom flanges 7 of said fillers are connected to the flange 3 on the bolster by rivets 8, portions of said bottom flanges 7 contacting with flanges at the bottom of the I-beam center sills. The bolster is provided with flanges 9, which form the sides of the central recess, and the center sills are held spaced away from said flanges

by fillers 10 consisting of approximately channel-shaped pieces 10, provided with a plurality of lugs 11, the rivets 6, which fasten the fillers 4 to the center sills, also passing through the lugs 11 and through the flanges 9 of the bolster, said fillers also contacting with the bottom flanges of the center sills, as shown in Fig. 2. A continuous tension-plate 12 is connected to the top flange 13 of the bolster and to the top flanges of the fillers 4 by rivets 14 and extends through slots 15 in the webs of the center sills, as shown clearly in Fig. 4. The continuous bottom flange 16 of the bolster is strengthened by tapered ribs 17, formed integral with the web of the bolster, and vertical ribs 18 are provided between said continuous bottom flange and the flange 3, on which the center sills rest.

The flanges 5, which form the sides of the central recess, are strengthened by horizontally-arranged tapered ribs 19, and the channels 20, forming the platform-sills, are connected by rivets 21 to vertical flanges 22, extending laterally from the web of the bolster, the top flanges and portions of the webs of said channels 20 being cut away, as shown in Fig. 3, so that the upper edges of said channels can lie flush with the upper edges of the center sills. One object of slotting the center sills to receive the continuous plate 12 is to enable the floor of the car to rest directly on the center sills, and thus provide a space underneath the floor to receive the pipes, wires, &c., with which the car is provided. As the means herein shown for connecting the ends of the bolster to the side sills of the car form no part of my present invention, it is not necessary to describe the same.

Having thus described my invention, what I claim as new, and desire to secure by Letters Patent, is—

1. A body-bolster consisting of a single casting of I form, a vertical flange projecting laterally from the web of said casting, and a channel-shaped sill connected to said vertical flange and having its top flange lying in a plane above the top flange of the bolster, a portion of the web and the top flange of said sill being removed to provide a clearance for the top flange of the bolster; substantially as described.

2. A body-bolster consisting of a casting provided at its central portion with a recess,

flanges forming the bottom and the sides of said recess, I-beam center sills resting on the bottom flange of the recess, flanged fillers arranged between the center sills, flanged fillers arranged between the outer faces of the center sills and the side flanges of the recess, the lower flanges of the I-beam center sills being engaged by said fillers, and a continuous tension-plate passing through slots in the webs of the center sills and being connected to the

bolster-casting and to the fillers between the center sills; substantially as described.

In testimony whereof I hereunto affix my signature, in the presence of two witnesses, this 20th day of March, 1906.

ALLEN E. OSTRANDER.
